UNITED STATES PATENT OFFICE.

ALBERT HENRY GODFREY GIRLING, OF HARLOW, ENGLAND.

BRAKING MECHANISM.

Application filed August 18, 1926, Serial No. 129,950, and in Great Britain May 12, 1925.

This invention relates to expanding brakes of the type wherein two brake levers, associated each with a brake shoe, are arranged to be moved apart by an expanding member 5 so as to force the shoes against a rotary member, such as a drum, to be braked. In such brakes the levers are usually mounted on separate fixed pivots or on one fixed pivot common to them both, and the frictional faces have heretofore usually formed a part of or been rigidly secured to the levers. This known arrangement has various defects, such as uneven wear owing to unequal 10 distribution of pressure over the frictional faces, which in turn reduces the effective 15 area of the frictional faces.

This invention has for one of its objects to increase the area of frictional face which shall be in use and thereby to increase the 20 life of the brake. Another object is to equalize the distribution of pressure over as large an area of the brake drum as possible and thereby reduce stresses tending to distort the drum. A further object is to 25 increase the power of brakes of the type described, without increasing their size. A still further object is to improve the clearance conditions between the brake shoes and the drum when the brake is not in use. Still 30 another object is to provide that a greater proportion of the bulk of the frictional liners can be worn away than heretofore, whereby the life of the brake is increased.

According to the invention there is provided in an expanding brake of the character described, the combination with a lever mounted to rock towards and away from a member to be braked, and means for rocking the lever, of brake shoes so pivotally 35 mounted one behind another on said lever as to co-operate in tandem with the member to be braked.

Other features of the invention will be described hereinafter and pointed out in the 40 claims.

Several embodiments of the invention are diagrammatically illustrated by way of example in the accompanying drawings, wherein—

Figure 1 is a side elevation showing an expanding brake of the type described according to the invention, the brake shoes on one brake lever being arranged differently, however, from those on the other, and

Figure 2 is a vertical section taken on the line 2—2 in Figure 1;

Figures 3 and 4 are like views respectively of a modified construction of brake according to the invention, part of the device having been removed in Figure 3; 60

Figure 5 is a diagram referred to herein-after;

Figure 6 is a side elevation of a single brake lever carrying shoes according to another form of the invention, and 65

Figures 7 and 8 are cross-sections taken respectively on the lines 7—7 and 8—8 in Figure 6.

Like reference numerals designate corresponding parts throughout the several 70 views.

Referring to Figures 1 and 2, the brake levers 20, 21 inside a rotary drum 22 are mounted to rock at one end, as about a fixed pivot-pin 23 which is preferably common to them both. A cam expander 24 operates with the other ends of the levers in the known manner for applying the brake, two springs 25 engaging both levers being provided as usual for contracting the 80 brake.

The brake levers 20, 21 carry each a pair of brake shoes 30, 30^a, 31 and 31^a, respectively, by means of pivot-pins 32 that pass through bosses in the webs of the shoes and 85 through the levers. As clearly shown in Figure 2, the shoes 30 and 30^a are of U section this being a simple and inexpensive construction, whilst the shoes 31 and 31^a are split in the direction of their length and 90 comprise two parallel side parts held together by fastening strips 33, the pivot-pins 32 on which they are mounted being integral with the lever 21. This arrangement is useful where there is only a small 95 space available for a lever of deep section, in which case to perforate the lever would unduly weaken it. The shoes 30 and 30^a can rock about their pivots independently of one another, but the shoes 31 and 31^a 100 have their adjacent ends so operatively connected as to cause them to rock in unison. As illustrated, the shoe 31 has a recess 34 in the form of an open-ended slot extending in the direction of length of the shoe, and 105 the shoe 31^a has a rounded lug 35 extending into the recess. It is to be understood that each lever 20, 21 may have the same construction and arrangement of shoes as the other if desired.

It will be observed that the frictional face of each shoe extends over about 90° of arc,

- and that their axes of pivoting lie on radii of the brake drum which are about 90° apart, so that the four shoes in one drum have a total frictional face nearly equal in length to the inner periphery of the drum. In this way a maximum area of frictional contact is obtained, approximately equal radial movement of the shoes is obtained at four points of the circumference of the internal periphery of the drum (i. e. at the said radii on which the pivots 32 lie) and owing to pivotally mounting the shoes substantially equal distribution of pressure over their whole area is ensured.
- To prevent noise from developing due to wear of the parts or chatter between the shoes and the drum, frictional devices in the form of anti-rattling devices may be provided for preventing the shoes from moving too freely. One form of such devices is shown in Figures 3 and 4.

In this construction of brake the two brake levers 40, 41 comprise each two arms lying side by side, between which the webs 25 and bosses of the shoes 42, 42^a and 42^b, are held by pivot-pins 43 that pass through the bosses. In Figure 3 one arm of the lever 41 is shown removed for the sake of clearness. Springs 44 which engage in slots in the webs of the shoes 42^a and 42^b, and at the underside of bosses on the lever arm serve to take up any backlash at the pivots and to prevent rattling by imposing a slight frictional restraint on the rotation of the shoes 30 about their pivots. The shoes 42^a and 42^b may be coupled together at their adjacent ends by a ball-and-socket joint (similar to that described in connection with Figure 1) so that they are compelled to rock in unison 40 for the purpose of equalizing the distribution of pressure.

Figure 5 is a diagram illustrating how the brake power is, under usual conditions, increased by an amount up to 40% or, under 45 special conditions, even more. In the ordinary brake shoe 50 used heretofore, in which the frictional face is rigidly connected with the brake lever, the center of braking pressure lies in a line 0. The braking pressure 50 which we may designate 0, in proportion to the cam force e , is equal to

$$e \left(\frac{m+n}{m} \right).$$

This will be apparent by taking moments about the fixed pivot point of the brake lever. In the case where m and n are equal, 55 the braking pressure equals $e \left(\frac{2}{1} \right)$, or $2e$.

As shown in Figure 5, m and n are equal to the distances from the center of braking pressure to the fixed pivot point of the brake lever and to the center of force applied by the cam 24 respectively. In the 60

present arrangement, the braking pressure is along the lines s_1 and s_2 . Designating the braking pressures as s_1 and s_2 respectively, the total braking pressure exerted may be summarized as follows:

$$s_1 = \frac{e}{2} \left(\frac{m+n}{p_1} \right),$$

by taking moments about the pivot point 23, 75 and

$$s_2 = \frac{e}{2} \left(\frac{m+n}{p_2} \right).$$

Inasmuch as m and n are equal and the angle between the lines of application of the 80 braking pressures and the line joining the pivot point 23 and the center of application of the cam force equals 45° , m and n may both be set equal to 1, and p_1 to .7. Therefore,

$$s_1 = \frac{e}{2} \left(\frac{1+1}{.7} \right) = 1.4e,$$

and $s_1 + s_2 = 2.8e$, namely 40% more than that developed by the ordinary brake shoe.

Figures 6, 7 and 8 show a brake shoe unit which can be applied to an existing brake of the type described. This unit comprises a brake lever 60 on which shoes 61, 62 are pivoted at 63 and 64, respectively. In order to prevent the shoes seizing on to their pivots 63, 64 by reason of rust, small bronze bushes 65 and 66 are pressed into the shoes 61, 62, respectively. In order to keep the shoes firmly down on to their pivots for preventing rattling and to take up slackness resulting from wear on the bushes or pivots, springs 67 and 68 are provided bearing on the top of the bushes. These springs are deflected by a pin 69 passing through the lever at their centres in order to create the necessary stresses on the bushes. The static stresses exerted by the springs 67, 68 also create sufficient friction between the respective parts between the shoes and the lever 60 to prevent the former from moving quite freely in relation to the latter, thus preventing chatter between the shoes and the brake drum when the brake is "off". The pivots 63, 64 are each prevented from moving out of place endwise by a small pin 70 that enters into an annular groove in the pivot and is held in place by a screw 71 carried by the shoe.

When the brake is commonly used in one direction of rotation the trailing ends of the shoes may be the longer than the leading ends, as shown at the bottom of Figure 1, thus providing increased area to support the pressure due to the moment about the pivot tending to rock the shoe. This moment is due to the tangential force developed at the frictional face and if not counterbalanced would tend to cause unequal wear at the ends of the shoe. Since at the 120

- adjacent ends of two shoes of equal length pivoted in the middle (Figure 6), the forces due to this moment are equal in amount but opposite in direction it is only necessary to 5 couple these ends together to negative the effect of the moment. In the construction shown in Figure 6 one end of the shoe 61 slidably bears on the adjacent end of the shoe 62.
- 10 As compared with brakes of the type described known heretofore the improved constructions according to the invention have, amongst others, the following advantages:
- 15 (1) The material increase of frictional or wearing area of the shoes gives increased life.
- (2) The very equal distribution of pressure over the entire area of the brake drum 20 reduces the stresses to which the drum is subjected and consequent drum distortion.
- (3) Owing to the forces expanding the 25 shoes being developed on radii at about 45° from the middle of the levers instead of at their centres, the mechanical advantage is increased and, consequently the power of the brake is increased by about 40%.
- (4) The clearance conditions between the 30 shoes and drum when not in use are improved. In known brakes of the type described the clearance space is a rigidly defined crescent-shaped area and, the frictional face being long, the clearances at the ends of the crescent are very small. In the 35 present brake the only rigid clearances lie along radii containing the shoe pivots, situated about 90° apart, and being much nearer the centre of the lever than the extreme ends of known liners the rigid clearance is greater. The clearances at the ends 40 of the shoes according to this invention are variable because each shoe can rock about its pivot.
- (5) A greater proportion of the bulk of 45 the frictional liner can be worn away than in brakes as constructed heretofore, because the smaller the angle subtended by the liner, the smaller the proportion of unavoidable waste.
- 50 (6) A brake lever provided with shoes according to the invention is interchangeable with existing brake levers and shoes, so that all the advantages of the present invention may be obtained in existing vehicles at a low cost and with a small expenditure of time.
- I claim:
1. In an expanding brake of the character 55 described, the combination with a lever mounted to rock towards and away from a member to be braked, and means for rocking the lever, of brake shoes so movably supported in tandem on said lever that when one end of either shoe moves away 60 from its supporting lever and towards the member to be braked, the other end of the same shoe, respectively, can move towards its supporting lever and away from the member to be braked.
2. In an expanding brake of the character 65 described, the combination with a lever mounted to rock towards and away from a member to be braked, and means for rocking the lever, of brake shoes so pivotally mounted in successive relationship on said lever as to co-operate in tandem with the member to be braked.
3. In an expanding brake of the character 70 described, the combination with a lever mounted to rock towards and away from a member to be braked, and means for rocking the lever, of brake shoes so pivotally mounted in successive relationship on said lever as to co-operate in tandem with the member to be braked, the adjacent ends 75 of which shoes are so operatively connected together as to cause the shoes to rock in unison on their supporting lever.
4. In an expanding brake of the character 80 described, the combination with a lever mounted to rock towards and away from a member to be braked, and means for rocking the lever, of brake shoes so pivotally mounted in successive relationship on said lever as to co-operate in tandem with the member to be braked, the adjacent ends 85 of which shoes are so operatively connected together as to cause the shoes to rock in unison on their supporting lever.
5. In an expanding brake of the character 90 described, the combination with a lever mounted to rock towards and away from a member to be braked, and means for rocking the lever, of brake shoes so pivotally mounted in successive relationship on said lever as to co-operate in tandem with the member to be braked, the adjacent ends 95 of adjacent shoes having respectively one a recess and the other a lug movable in the recess.
6. In an expanding brake of the character 100 described, the combination with a lever mounted to rock towards and away from a member to be braked; and means for rocking the lever, of brake shoes so pivotally mounted in successive relationship on said lever as to co-operate in tandem with the member to be braked, the pivotal axis of 105 each shoe being situated nearer one end of the same than the other.
7. In an expanding brake of the character 110 described, the combination with a lever mounted to rock towards and away from a member to be braked, and means for rocking the lever, of brake shoes so pivotally mounted in successive relationship on said lever as to co-operate in tandem with the member to be braked, the trailing end of each shoe being longer than the leading end.
8. In an expanding brake of the character 115 described, the combination with a lever mounted to rock towards and away from a member to be braked, and means for rocking the lever, of brake shoes so pivotally mounted in successive relationship on said lever as to co-operate in tandem with the member to be braked, and anti-rattling 120 means tending to prevent movement of the shoes in relation to the supporting lever.
9. In an expanding brake of the character 125 described, the combination with a lever

- mounted to rock towards and away from a member to be braked, and means for rocking the lever, of brake shoes so pivotally mounted in successive relationship on said lever as to co-operate in tandem with the member to be braked, and resilient means constituting an anti-rattling device tending to prevent the shoes from rocking about their pivotal axes.
9. In an expanding brake of the character described, the combination with a lever mounted to rock towards and away from a member to be braked, and means for rocking the lever, of two brake shoes so pivotally mounted in successive relationship on said lever as to co-operate in tandem with the member to be braked, and a spring common to both shoes tending to hold the pivots of the shoes against rattling on the lever supporting them.
10. In an expanding brake of the character described, a combination with a brake lever of a plurality of transverse pivot pins on said lever between its ends, a plurality of brake shoes mounted to rock about said pivot pins and coat with a member to be braked, a plurality of bushes in the shoes adapted to receive the pivot pins, and springs carried by the lever and bearing upon the bushes.
11. In an expanding brake of the character described, a combination with a brake lever of a plurality of transverse pivot pins mounted to move endwise between said levers between its ends, a plurality of brake shoes of U section embracing said lever, and mounted between its ends on said pivot pins, bushes in the shoes adapted to receive the pivot pins, a plurality of bearings carried by the lever and bearing on the bushes, and means for locking the pivot pins against longitudinal movement in said lever.
12. In an expanding brake of the character described, the combination with a brake lever, of a transverse pivot-pin mounted to move endwise in said lever between its ends, a brake shoe of U section embracing said lever and mounted between its ends on said pivot-pin that extends at both ends into the sides of the shoe, two bushes in the shoe, each receiving one end of the pivot-pin, two springs carried by the lever and bearing each on one of said bushes, and means for locking said pivot-pin against endwise movement in said lever.

In testimony whereof I affix my signature.

ALBERT HENRY GODFREY GIRLING.
